UNITED STATES PATENT OFFICE.

JULIUS C. GOODWIN, OF PHILADELPHIA, PENNSYLVANIA.

SEWING-MACHINE.

1,088,339.

Specification of Letters Patent. Patented Feb. 24, 1914.

Application filed November 27, 1911. Serial No. 662,545.

To all whom it may concern:

Be it known that I, JULIUS C. GOODWIN, a citizen of the United States, residing at Philadelphia, in the county of Philadelphia 5 and State of Pennsylvania, have invented certain new and useful Improvements in Sewing-Machines, of which the following is a specification.

My present invention relates to improvements in sewing machines adapted to form a seam for uniting and covering the edges of two fabrics at one operation, such for instance as the seam forming the subject matter of Letters Patent issued to me December 12, 1911, No. 1,011,186. My improvements in the present case relate to mechanism for forming such a seam which is characterized by a longitudinal line of stitches intersected by cross-bars on the upper surface of the fabric and a similarly disposed longitudinal line of loops on the under surface of the fabric intersected by transverse loops.

The object of my invention is to produce a simple and effective spreader for the upper thread carrying mechanism together with mechanism for operating the same which will be reliable in its action at all times particularly when running at a high rate of speed.

A further object of my invention is to construct the spreader and its connections so that the same may be raised and lowered as the presser-foot is raised and lowered 35 without disconnecting any of the spreader mechanism.

In carrying out my invention I employ only such movable parts as will be positive in their operation thus rendering the mechanism nearly free from lost motion such as would tend to set up unnecessary vibrations. The movable parts of the device are at once simple and durable in construction and well adapted to meet the present demand for a high speed power driven sewing machine suited to a special class of factory work.

As the construction and operation of sewing-machines are now well known I have omitted as far as possible the lower stitch forming mechanism and have illustrated and will proceed to describe such parts only as are immediately concerned with my present improvements.

The various features of novelty which 55 characterize my invention are pointed out

with particularity in the claims annexed to and forming a part of this specification. For a better understanding of the invention however, and the advantages possessed by it, reference may be had to the accompanying 60 drawings and descriptive matter in which I have illustrated and described one of the forms in which my invention may be embodied.

Referring now to the drawings:—Figure 65 1 illustrates a side elevation of a sewing machine embodying my invention. Fig. 2 represents a sectional plan view, the section being indicated by the dotted line 2—2 in Fig. 1 and Figs. 3 and 4 are detached perspective views showing two positions of the spreader.

As shown in the drawings my invention is preferably used in connection with a sewing machine of the type employed in forming the so called elastic or chain stitch. It should be stated, however, that my improvements may be employed in connection with other types of sewing machines without departing in any way from the principle of 80 my invention.

In the drawings:—A, indicates the bed-plate of the machine which as shown in Fig. 1, is provided with bearings A¹ A¹ to support a main shaft B. The driving shaft B 85 is provided with a hand wheel B¹, a grooved driving pulley B² and eccentrics B³ and B⁴, which latter transmit motion directly to a spreader mechanism as will be hereinafter described. Extending upward from the bed-plate is a curved arm A², which constitutes a portion of the fixed frame of the machine and is provided with bearings A³ and A⁴ to guide a vertically reciprocating needle-bar C. The needle-bar is operated by an eccentric B⁵, fastened to the shaft B, at a point adjacent to the driving pulley B². Motion is transmitted to the needle-bar by an eccentric lever B⁶, connected by a ball and socket joint B⁷, to the short arm B⁸, of a curved lever B⁹, which in turn is connected by a link B¹⁰, to a sleeved connection B¹¹, on the needle-bar. The lower end of the needle-bar C is provided with a collar C¹ provided with 90

suitable openings to receive needles C² and C³. Arranged in line with the needle bar C, is a presser-bar D, provided with a presser-foot D¹, normally pressed downward by a leaf spring D², one end of which is fastened to the frame of the machine at 100

105

110

a point D^3 , while the other bears upon a pin formed integral with a sleeve D^4 , and fastened to the presser-bar.

As shown in Fig. 1, the tension of the 5 spring D^2 may be increased or diminished by means of a thumb screw D^5 , which is threaded to a projection on the frame of the machine and bears directly upon the spring.

As the lower stitch forming mechanism or 10 looper mechanism forms no part of the present invention it is not thought necessary to describe the same except in a general way. For convenience of illustration I have indicated by dotted lines in Fig. 1 the conventional looper mechanism employed in well 15 known machines of this type in which a looper lever E , carrying a curved looper E^1 , is caused to oscillate upon an axis E^2 , by a connecting rod E^3 , interposed between a depending portion E^4 of the arm B^6 , and the 20 head of the looper lever E . Other mechanism heretofore suggested for a similar purpose may be employed in lieu of the looper mechanism just mentioned such for instance 25 as the mechanism shown and described in Letters Patent No. 909,081, dated January 5, 1909.

The spreader mechanism which constitutes the essential feature of my invention, 30 comprises a horizontally disposed spreader-rod F^1 , to which is adjustably secured the collar F^2 , of a spreader-arm F^3 , the latter having an opening to receive a spreader F . The spreader F is provided at its lowermost 35 portion with a finger f , adapted to carry the thread of the needle C^2 , beyond the path of the needle C^3 .

The spreader-rod F^1 , is journaled in bearings F^4 and F^5 , the former being pivoted to 40 an arm F^6 , which is carried by a rod F^7 , controlled by the presser-bar D , and the latter being pivoted to a projection A^6 , connected to or forming part of the frame of the machine.

45 The means employed to operate the spreader-rod F^1 , comprises the eccentric B^3 , which is provided with a pitman G , connected by a ball and socket joint G^1 , to an arm G^2 , fastened to the spreader-rod F^1 . 50 A plate g^1 , located near the end of the arm G^2 , serves to prevent the pitman from turning.

By the means just mentioned the spreader-rod is given an oscillatory or rocking motion in its bearings which directs the finger of the spreader into and out of the path of the needles C^2 and C^3 .

While the oscillatory motion is being imparted to the spreader-rod the same must be 60 given a reciprocating motion in its bearings in order that the finger of the spreader may carry a thread of the needle C^2 , into the path of the needle C^3 , and this motion is obtained in the following manner: Loosely 65 journaled on the spreader-rod F^1 , is a sleeve

H , guided between collars H^2 and H^3 and provided with a boss H^1 , to which is connected by links H^4 , H^5 a bell crank lever H^6 . The bell crank lever H^6 , is pivoted to a stud H^6 , formed on the lower frame work of the 70 machine and has a short arm h^5 , coupled to an angular link H^7 , which is connected by a ball and socket joint H^8 to an eccentric lever H^9 , controlled by the cam B^4 . By the mechanism just described the spreader-rod F^1 75 and spreader F have imparted to them a reciprocating motion. By the joint action of the mechanism described for producing simultaneously a reciprocating motion and an oscillatory motion of the spreader-rod and spreader, the finger of the spreader is caused to travel in a path somewhat elliptical. By this means the thread carried by the needle C^2 , is caught up by the finger of the spreader and carried in the form of a loop slightly 80 beyond the path of the needle C^3 , permitting the needle C^3 in its downward movement to engage the loop formed in the thread carried by the needle C^2 , before said loop has been released by the finger of the 85 spreader.

The spreader F , together with the forward end of the spreader rod is under control of the presser-bar D , to the extent that when the presser-bar is raised or lowered 90 by means of a cam shaped lever D^5 , the spreader will also be raised or lowered to prevent its interference with the movement of the presser-foot.

While I have shown and described what I 100 consider the preferred form of mechanism embodied in my improvement it will be understood that structural changes or modification in the several parts may be made without departing from the scope of my invention.

Having described my invention, what I claim, and desire to secure by Letters Patent, is—

1. In a sewing machine, the combination 110 of a spreader-rod, a vertically movable presser-rod, pivoted bearings in which the spreader rod is journaled, one of said pivoted bearings having a fixed bearing in the frame of the machine and the other a bearing in a connection of said vertically movable presser-rod, a spreader suitably mounted upon the spreader-rod, and means for oscillating and simultaneously reciprocating the spreader-rod.

2. In a sewing machine, the combination 115 of a main shaft and driving mechanism, a horizontally extending presser-foot, vertically extending needles, a spreader mechanism comprising a horizontally extending spreader-rod provided with a spreader having a finger adapted to deflect the needle threads, an eccentric on the driving shaft, a bell crank lever having a swivel connection with said eccentric and a similar con- 120

nection with the spreader-rod to impart a horizontal reciprocating motion to the spreader-rod and spreader, an eccentric operated by the driving shaft, and a rod 5 on the last named eccentric swiveled to an arm on the spreader-rod to impart an oscillating motion to the spreader-rod and spreader.

3. In a sewing machine, the combination 10 of the driving mechanism, a spreader-rod, a presser-bar and a presser foot carried thereby, pivoted bearings in which the spreader-rod is journaled, one of said bearings being pivoted to the fixed frame, means connected 15 to the presser-bar and on which the other bearing is pivoted, a spreader suitably mounted upon the spreader-rod and a finger on its depending end to deflect the needle threads, means to impart both a reciprocating 20 and oscillating motion to the spreader-rod, and means for lifting the spreader with the presser-foot.

4. In a sewing machine, the combination 25 of the frame and driving mechanism, a spreader mechanism comprising a longitudinally disposed spreader-rod, pivoted bearings in which said spreader-rod is journaled, said bearings being arranged above the bed- 30 plate of the machine, a presser foot, a bar connected thereto, and an arm controlled by the bar, one of said bearings being pivoted to the frame of the machine and the other to said arm, a spreader adjustably secured to the spreader-rod, a finger on the spreader

adapted to engage the needle threads, an eccentric and connections controlled by the driving mechanism to impart a horizontally reciprocating motion to the spreader-rod and another eccentric and connections controlled by the driving mechanism to impart 35 an oscillating motion to the spreader rod. 40

5. In a sewing machine, the combination with the lower stitch forming mechanism including an oscillatory looper, a needle bar 45 provided with thread carrying needles, a spreader mechanism comprising a spreader-rod journaled in pivoted bearings one of which is fulcrumed upon an arm controlled by the bar of the presser-foot, a spreader 50 mounted upon the spreader-rod and provided with a finger to deflect the needle threads of the upper stitch forming mechanism, a driving shaft, an eccentric mounted thereon and provided with suitable connections adapted to impart a horizontally reciprocating motion to the spreader mechanism and another eccentric mounted on said shaft and so connected to the spreader mechanism as to impart thereto an oscillatory movement. 55

In testimony whereof I affix my signature in presence of two witnesses.
